Inventor:

By Charles Turner Brown,
Atty.

UNITED STATES PATENT OFFICE.

MEAD E. GOODHUE, OF CHICAGO, ILLINOIS, ASSIGNOR TO CHICAGO FEATHER DUSTER CO., OF CHICAGO, ILLINOIS, A CORPORATION OF ILLINOIS.

FRAME FOR WALL-BRUSHES.

No. 907,337.

Specification of Letters Patent.

Patented Dec. 22, 1908.

Application filed July 16, 1908. Serial No. 443,929.

To all whom it may concern:

Be it known that I, MEAD E. GOODHUE, a citizen of the United States, and a resident of Chicago, in the county of Cook and State 5 of Illinois, have invented certain new and useful Improvements in Frames for Wall-Brushes, of which the following, when taken in connection with the drawing accompanying and forming a part hereof, is a full and 10 complete description sufficient to enable those skilled in the art to which it pertains to understand, make, and use the same.

This invention relates to frames over 15 which lamb's wool is sewed to make brushes used for dusting hardwood floors, walls, ceilings and the like. And the object of this invention is to obtain an economically made, flexible and resilient frame, to which a handle can be attached; a frame which will be 20 durable and one which will retain its resiliency for a considerable time, when used.

A further object of the invention is to obtain a frame which in use will remain substantially flat on the front edge thereof and 25 thereby force the lamb's wool, or other covering thereof, against the object wiped thereby.

In the drawing referred to Figure 1 is a 30 front elevation of a frame embodying this invention. Fig. 2 is an end elevation of a frame embodying this invention. And Fig. 3 is a vertical sectional view on line 3—3 of Fig. 1, viewed in the direction indicated by the arrows.

35 A reference letter applied to designate a given part is used to indicate such part throughout the several figures of the drawing wherever the same appears.

A is a socket provided with internal screw 40 threads which are indicated by broken lines in Fig. 1 of the drawing and lettered *a*. A handle having corresponding screw threads may be attached to socket A, by turning the screw threads on the handle into the screw 45 threads *a*, in the socket, in the usual way of attaching handles to sockets.

B is a wire, bent at *b*, *b'*, *b''*, and *b'''*, which is put through the hole (C) provided therefor in the socket A, (as is indicated by broken 50 lines in Fig. 1), and the ends joined, as at D.

E is a wire bent at *e*, *e'*, and put through the hole F provided therefor in the socket A, (as is indicated by broken lines in Fig. 1), and attached to the wire B at *f*, *f'*, by bending the 55 ends *G*, *G'*, over the wire B. The wire B is

provided with bends at *f*, *f'*, where the ends *G*, *G'*, of wire E are bent thereonto, as described, to prevent a sliding or slipping movement of wire E on wire B.

Wire B, when bent up as described forms a 60 rectangle, and the wire E is attached to wire B in such manner as to draw the sides H, *h*, of the rectangle out of a straight line, (as lines I, *i*). The wire E is, by this construction, put under tension, and the resiliency 65 thereof tends to maintain wires B and E in the position illustrated in Figs. 1 and 2; and when the frame formed by such wires is forced into the position illustrated in Fig. 3 the wire B turns in hole C in the socket, as on 70 a fulcrum and the wire E turns in hole F in the socket as on a fulcrum; and hence, wire E will draw side H of the rectangle formed by wire B out of the curved line in which it would otherwise move, say line J, towards 75 the curved line *j* in which the ends *G*, *G'*, move; thus increasing the tension of the spring formed by wire B. The increased tension of the spring B thus obtained tends to return the wires B and E into their initial 80 position, and such wires are thus so returned by the resiliency thereof as the pressure thereon is relieved.

Having thus described my invention, what I claim as new and desire to secure by Letters Patent is,—

1. A rectangular frame made of bent up 90 resilient wire, a socket provided with holes therethrough, the frame and socket joined by one of the sides of the frame passing through one of the holes in the socket, an additional wire also passing through one of the holes in the socket, such additional wire bent up and the ends thereof turned over one of the sides of the frame, such frame, 95 socket and additional wire associated so that the longer sides of the frame are drawn out of a straight line by the additional wire; substantially as described.

2. A socket provided with internal screw 100 threads in combination with a wire bent up to obtain a rectangle and the ends of the wire joined, such socket provided with holes therethrough and one of the longer sides of the rectangle put through one of the holes in the socket, an additional wire put through 105 the remaining hole in the socket and bent up to and connected with the remaining longer side of the rectangle, such additional wire arranged to draw the longer sides of the rec- 110

tangle out of a straight line; substantially as described.

3. A socket provided with internal screw threads in combination with a wire bent up to obtain a rectangle, the ends of the wire joined and the wire on one of the longer sides of the rectangle bent to obtain an indenture, such socket provided with holes therethrough and one of the longer sides of the rectangle put through one of the holes in the socket, an additional wire put through the

remaining hole in the socket and bent up to and connected with the remaining longer side of the rectangle and at the indentured points thereof, such additional wire arranged to draw the longer sides of the rectangle out of a straight line; substantially as described. 15

MEAD E. GOODHUE.

In the presence of—

CORA A. ADAMS,

CHARLES TURNER BROWN.
